ROY J. POMEROY, OF LOS ANGELES, CALIFORNIA

SOUND RECORDING SYSTEM

Application filed March 18, 1929. Serial No. 347,886.

This invention relates to the photographic recording of sound, and is broadly concerned with a light valve method for producing a record of the variable width type. Although the present invention is well adapted to produce the present known variable width record having a single serrated edge, the preferred form of the invention produces a variable width record having a double serrated edge.

The variable width type of record has certain well recognized advantages over the variable density type. Among these may be mentioned, first, that both the negative and positive variable width records are suitable records for reproduction; while, as is well known, a negative of the variable density type is not suitable for reproduction, only the positive being a true sound record. And, second, a serious and difficult problem exists in making the variable density record of an exactly proper density and contrast for undistorted reproduction. Obviously, this problem does not exist in the processing of variable width records.

The present invention provides a method and system for producing a variable width record, for instance, with the use of the well known light valve embodying a current carrying loop of metallic ribbon strung in a magnetic field longitudinally over a rectangular light aperture, and electro-magnetically vibrated transversely of the light aperture to control the quantity of light passing therethrough. This light valve was originally developed for the purpose of producing the variable density type of record, and is a very accurately responsive device for producing records of that type. The device is equally well adapted, however, to function according to the present invention to produce an extremely accurate and undistorted variable width record, of either the known single-serrated-edge type, or of an improved double-serrated-edge-type first provided by the present invention. The specific double-serrated-edge record has certain features of improvement as regards accuracy of reproduction, increased volume without distortion, etc., which will appear later.

While the invention is to be hereinafter illustrated and described particularly in connection with the specific light valve above referred to, it will be recognized that other light valve devices may be found suitable and may be substituted if desired.

With this preliminary discussion in mind, the invention will best be understood from the following detailed description of present preferred means for carrying the invention into effect, reference for this purpose being had to the accompanying drawings, in which:

Fig. 1 is a diagrammatic view of a system embodying my invention;

Fig. 2 is an interior elevation of the front pole piece assembly of the preferred light valve, showing the light-valve ribbon and light-slit, this view being taken on line 2-2 of Fig. 1;

Fig. 2a is a similar view of a modified light valve adapted to produce the single-serrated-edge type of record;

Fig. 3 shows the negative double-serrated-edge sound record obtained in the system of Fig. 1, using the light valve illustrated in Fig. 2;

Fig. 4 shows a positive of the negative record shown in Fig. 3;

Fig. 5 shows a negative single-serrated-edge record obtained with the use of the light valve shown in Fig. 2a;

Fig. 6 shows a positive of the negative record illustrated in Fig. 5;

Figs. 7 and 8 indicate diagrammatically the relations of the light valve aperture and image thereof to the film in a well known prior sound recording system utilizing the specific light valve included in the preferred embodiment of the present invention; and

Figs. 9 and 10 indicate diagrammatically the relations of the light valve aperture and image thereof to the film according to the present invention.

In Fig. 2 is shown an interior elevation of the front pole piece assembly of a typical well known type of light valve, the light valve being generally indicated at L in Fig. 1. This assembly includes an iron plate 10 which forms a part of the core 11 of a mag-

netic field winding 12 (see Fig. 1), and also serves as a base for light valve elements now to be described. A pair of opposed capstan screws 13 are mounted at one end of plate 10, 5 and wound upon the ends of these screws are the ends of a loop 14 of metallic ribbon, the looped end of which is supported at the other end of plate 10 by means of a spring-held pulley 15 mounted thereupon. The ribbon 10 may be tensed to a natural frequency of approximately 7,000 vibrations per second. The central portion 14a of the loop is supported by a pair of spaced insulating bridges 17 secured to plate 10, and having notches 15 18 which space the adjacent edges of the loop normally at a distance of about 2 mils. Plate 10 is provided with a raised pole piece 20, the upper face 21 of which is spaced just below the central portion 14a of the metallic 20 loop. A tapered light slot 22 is provided through pole piece 20 and plate 10 (see Fig. 1), and opens in pole piece face 21 to form a slit 25 parallel to and just below loop 14. In the present instance this slit is made 8 mils 25 wide. The loop normally covers the two sides of the slit, thereby reducing the light opening to a normal slit 2 mils in width.

In operation, field winding 12 is energized by a constant direct current, and a strong 30 magnetic field exists between pole piece 20 and an opposed pole piece provided on core 11, as indicated at 26 in Fig. 1. A modulated electrical current passed through the metal loop 14 causes the sides of the loop 35 to be vibrated or bowed in and out due to electro-magnetic action with the magnetic field. The sides of the loop are thus caused to open and close, thereby varying the horizontal dimension of the light opening or slit 40 of the valve in accordance with the pulsations of the sound-modulated current.

The light valve as now described has commonly been used to make a variable density record by moving a sensitized film transverse- 45 ly to the light valve loop and slit, and forming an image of the light valve slit transversely on the film. In Fig. 7 the light valve slit is indicated at P, the letter W indicating the constant dimension and the letter D indicating the variable dimension thereof. According to this prior system, the film, indicated at F, is moved transversely to the slit as diagrammed. In Fig. 8 is shown the image P' of the slit which is formed upon the film. 50 It is to be noted that the slit image is positioned with its sides of constant dimension W' transverse to the direction of film movement, and with its sides of variable dimension D' in the direction of film movement. 55 The resulting record is, of course, of the well known constant width, variable density type.

According to the present invention, as distinguished from the system just described, the film is moved in the same direction as the 60 light valve loop and slit. In Fig. 9 the light

valve slit is again indicated at P, the latter W indicating the constant dimension and the letter D indicating the variable dimension thereof. But in this case the film, indicated at F, is moved in the direction of the slit. In Fig. 10 is shown the image p of the slit which is formed upon the film, w representing the constant dimension and d the variable dimension thereof. In this case the dimension w is compressed relatively to the dimension d, the reason for which being set out later. It is to be noted that in the present case the slit image is positioned with its sides of variable dimension d transverse to the direction of film movement, and with its sides of constant dimension w in the direction of film movement. This arrangement, as may readily be seen, will produce a record of variable width.

The light valve is understood to be situated in the system of Fig. 1 with its loop 14 extending vertically, the action being that the horizontally vibratory vertical loop varies the horizontal width of the vertically extending slit of the valve. In Fig. 1 the letter H represents a lamp house, and C a condenser which is adapted to throw light therefrom upon the light valve loop through a tapered light slot 29 provided in the central portion of core 11. An objective O located before the slit, is proportioned and relatively positioned to form a relatively large image thereof in the plane of the vertically moving film F, which film may be driven by any well known means that will impart a constant forward motion thereto. A plano-cylindric lens T is preferably placed between objective O and film F, and is situated with its plane face toward the objective, and with the axis of its cylindric surface horizontal—that is, at right angles to the direction of the light valve slit. Due to the characteristic of the plano-cylindric lens the image of the light valve slit is flattened or compressed vertically in its constant dimension w, thereby concentrating the light rays and intensifying the image, while the horizontal dimension d of the image remains of good size, being preferably one-tenth of an inch when the light valve slit is modulated at full amplitude.

There is preferably placed before film F a vertical plate A having a relatively narrow horizontal slit S in the path of the light rays, the function of this slit being to define sharply the upper and lower edges of the image formed upon the film. It will be noted, upon consideration, that with the use of this slit it is not necessary to have the light valve slit of any definite length.

It may be seen that there is formed on the film transversely to its direction of movement an elongated image of varying length but of constant intensity; and that there is accordingly printed upon the film a record

band of variable width and constant density.

The resulting negative record is shown in Fig. 3, in which the sound track is seen to comprise a central opaque band 35, both edges 5 of which are serrated in accordance with the recorded vibrations of the two sides of the light valve loop. This double-serrated-edge opaque band 35 lies in a clear transparent field 36. The corresponding positive record, 10 illustrated in Fig. 4, comprises a double-serrated-edge transparent band 35a, lying in an opaque field 36a. The positive and negative records represent the original sound equally well, and either may be used in re- 15 production.

A modified light valve arrangement for making a single-serrated-edge record according to the present invention is shown in Fig. 2a. In this view, parts corresponding to similar parts in the form shown in Fig. 2 will be 20 designated by like numerals with the sub-letter *a*. In this case a single strip 38 of metal ribbon is utilized, one end of the ribbon being wound upon the end of a capstan screw 25 40 mounted at the lower end of the plate, the ribbon thence passing over insulating bridges 17a, which support the ribbon to partially cover light slit 25a of pole piece 20a, and the ribbon being tensed and secured at its other 30 end by passing over a spring-held pulley 15a and then down to be wound upon a capstan screw 41 mounted at the upper end of plate 10. It will readily be understood that with this 35 light valve arrangement situated in the system of Fig. 1, the image cast upon film F will have one straight edge representing the uncovered edge of slit 25a, and one varying edge representing the vibrating light valve ribbon 38. The resulting negative record, 40 shown in Fig. 5, is comprised of an opaque band having one straight and one serrated edge, lying in a transparent field 46. The positive record, of course, is the photographic reverse, as shown at 45a and 46a in Fig. 6. 45 Either the positive or negative is a suitable record for reproduction, as before.

Although the invention has been illustrated with specific forms of light valves, it 50 will be understood that any other suitable light valve adapted to vary a linear dimension of a light slit under sound-modulated current actuation may be substituted, if desired.

It may now be seen that I have provided a 55 system by which extremely accurate and undistorted records of the variable width type may be produced. And I have further provided a system for making a record of this general type having specifically a double- 60 serrated edge, with the accompanying advantages hereinbefore referred to.

It will be recognized that the illustrative 65 system specifically described herein is capable of considerable modification and rearrangement without departing from the spirit and

scope of my invention; and it is therefore to be understood that the following claims embrace all such modifications and equivalent arrangements as may fairly be construed to fall within the scope of my invention.

70

I claim:

1. In a sound recording system, the combination of means forming a substantially rectilinear light aperture, sound-actuated means for varying a linear dimension of said aperture, means for illuminating said aperture, means for moving a sensitized film, an optical system adapted to form in the plane of said moving film, an image of said aperture with its varying dimension transverse 80 to the direction of film movement, and an aperture plate having a relatively narrow slit in said optical system adapted to restrict the light rays reaching the film to form an image having a dimension in the direction of film movement relatively narrow as compared with its dimension transverse to the direction of film movement.

75

2. In a sound recording system, the combination of means forming a substantially rectilinear light aperture, sound-actuated means for varying a linear dimension of said aperture, means for illuminating said aperture, means for moving a sensitized film, an optical system adapted to form in the plane of said moving film an image of said aperture with its varying dimension transverse to the direction of film movement, and means for restricting the dimensions of the image in the direction of film movement to a dimension less than the normal image in a direction transverse to the direction of film movement.

85

3. In a sound recording system, the combination of means forming a substantially rectilinear light aperture, sound-actuated means for varying a linear dimension of said aperture, the other linear dimension thereof remaining constant, means for illuminating said aperture, means for moving a sensitized film, and an optical system adapted to form in the plane of said moving film an aperture image relatively compressed in its constant linear dimension, and with its varying dimension transverse to the direction of film movement.

90

4. In a sound recording system, the combination of means forming a substantially rectilinear light aperture, sound-actuated means for varying a linear dimension of said aperture, the other linear dimension thereof remaining constant, means for illuminating said aperture, means for moving a sensitized film, an optical system adapted to form in the plane of said moving film an aperture image relatively compressed in its constant linear dimension and with its varying-dimension sides transverse to the direction of film movement, and an aperture plate having a narrow slit in said optical system, adapted to restrict the image formed on the film to a relatively 100 105 110 115 120 125 130

small dimension in the direction of film movement.

5. In a sound recording system, the combination of means forming a substantially rectilinear light aperture, sound-actuated means for varying a linear dimension of said aperture, the other linear dimension thereof remaining constant, means for illuminating said aperture, means for moving a sensitized film, and an optical system including an objective and a cylindric lens adapted to form in the plane of said moving film an aperture image relatively compressed in its constant linear dimension, and with its varying dimension transverse to the direction of film movement.

6. In a sound recording system, the combination of means forming a substantially rectilinear light aperture, sound-actuated means for varying a linear dimension of said aperture, the other linear dimension thereof remaining constant, means for illuminating said aperture, means for moving a sensitized film, an optical system including an objective and a cylindric lens adapted to form in the plane of said moving film an aperture image relatively compressed in its constant linear dimension and with its varying dimension transverse to the direction of film movement, and an aperture plate having a narrow slit in said optical system adapted to restrict the image formed on the film to a relatively small dimension in the direction of film movement.

35 7. In a sound recording system, the combination of means forming an elongated light slit, means to move a light-sensitive film in a direction lengthwise of the light slit, sound-actuated means for varying the narrower dimension of the light slit, means to project an image of the light slit on the film, and means to restrict said image on the film to a relatively small dimension in the direction of film movement.

45 8. In a sound recording system, the combination of means forming an elongated light slit, means to move a light-sensitive film in a direction lengthwise of the light slit, sound-actuated means for varying the width of the light slit, and optical means for projecting an image of the light slit on the film, said optical means including means to restrict said image on the film to a relatively small dimension in the direction of film movement.

55 9. In a sound recording system, the combination of means forming an elongated light slit, means to move a light-sensitive film in a direction lengthwise of the light slit, sound-actuated means for varying the width of the light slit, and optical means for projecting an image of the light slit on the film, said optical means including means for relatively compressing the image in the direction of film movement.

65 10. In a sound recording system, the com-

bination of means forming an elongated light slit, means to move a light-sensitive film in a direction lengthwise of the light slit, sound-actuated means for varying the width of the light slit, and optical means for projecting an image of the light slit on the film, said optical means including means for relatively compressing the image in the direction of film movement to a dimension less than the normal image dimension in the direction transverse of the film movement.

11. The method of sound recording that includes varying one linear dimension only of a light slot by sound wave actuation, and projecting an image of the light slot onto a moving light-sensitive film with the varying dimensions of the image transverse to the direction of film movement and relatively compressing said image in its dimension in the direction of film movement.

12. The method of sound recording that includes, varying the narrower dimension of an elongated light slot by sound wave actuation, and projecting an image of the light slot onto a light-sensitive film moving in the direction of elongation of the light slot, with the varying dimension of the image transverse to the direction of film movement.

In witness that I claim the foregoing I have hereunto subscribed my name this 21st day of February, 1929.

ROY J. POMEROY.
